UNITED STATES PATENT OFFICE.

HENRY C. SERGEANT, OF NEW YORK, N. Y.

SUPPORT FOR ROCK-DRILLS.

SPECIFICATION forming part of Letters Patent No. 337,526, dated March 9, 1886.

Application filed December 24, 1885. Serial No. 186,594. (No model.)

To all whom it may concern:

Be it known that I, HENRY C. SERGEANT, of the city and county of New York, in the State of New York, have invented a new and 5 useful Improvement in Supports for Rock-Drills, of which the following is a specification.

Rock-drills are ordinarily provided with a drill-back wherein the cylinder is moved longitudinally to feed the drill or bit forward as the work progresses; and this drill-back is clamped in a support, whereby it is held immovable during the drilling operation, but which may be adjusted to change the position 15 and direction of the drill-rod when desired. In certain kinds of work the drill-back is supported by a tripod, consisting of two hip-pieces, an interposed body portion or drill-support, and legs which are connected with the hip- 20 pieces. For other kinds of work the drill-back is supported by a clamp which is adjustably secured upon an upright column, or upon an arm projecting laterally from such column.

One feature of my invention consists in a 25 novel construction of the part in which the drill-back is held, whether it be the body portion of the tripod, or a clamp which is to be secured upon an upright column or an arm projecting therefrom; and another feature of 30 my invention consists in a novel construction of the parts, whereby the side legs of the tripod are adjustably secured to the hip-pieces thereof, so that said legs may be swung in planes parallel with or at right angles to such 35 hip-pieces, and so that a single bolt serves to secure each side leg in position against swinging in either of said planes when the nut thereon is tightened.

In the accompanying drawings, Figure 1 is 40 a vertical section through the upper portion of a tripod embodying my invention. Fig. 2 is an elevation thereof, looking toward the left-hand of Fig. 1. Fig. 3 is a horizontal section upon the plane of the dotted line $x-x$, Fig. 2. Fig. 4 is a vertical section upon the plane of the dotted line $y-y$, Fig. 2. Fig. 5 is a sectional view of a clamp and drill-back support, which is to be employed for holding the drill upon an upright column or an arm projecting therefrom. Fig. 6 is a plan view looking from the top of Fig. 5; and Fig. 7 is an

elevation looking from the left-hand of Fig. 5.

Similar letters of reference designate corresponding parts in all the figures.

Referring first to the construction shown in 5; Figs. 1, 2, 3, and 4, A designates the two hip-pieces of the tripod, which are parallel with each other, and between which are arranged the body portion B of the tripod, and a sleeve, C, which forms the upper portion of the back 6c leg, C'. The sleeve C has conical end portions, which fit in correspondingly-conical trunnion-bearings, a, in the hip-pieces A, and the sleeve is secured against turning relatively to the hip-pieces by a central bolt, b, which passes through 65 the sleeve and hip-pieces, as best shown in Fig. 3, and by which the swinging of the back leg, C', in a plane parallel with the hip-pieces is controlled.

The body portion B of the tripod extends 70 between the hip-pieces, and is provided at the end with conical trunnions b', which fit in correspondingly-coned trunnion-bearings a' in the hip-pieces A, as best shown in Fig. 3.

D designates a bolt, which extends through 75 the body B, and also through the hip-pieces, and is provided at its end or ends with a nut or nuts, e, by tightening which the trunnions b' may be brought to a tight bearing in the trunnion-bearings a', and the turning or swinging 80 of the body B relatively to the hip-pieces A be controlled. On the outer side of each hip-piece A is a journal or trunnion, A', which is surrounded by a band, E, said band being split or divided at d, as best shown in Fig. 4. 85 In each band is a conical trunnion-bearing, d', which receives a conical trunnion, e, upon the head of the side leg, F, as best shown in Fig. 4, and each side leg and the band E, with which it is connected, are secured in place by 90 a bolt, e', extending through the divided portions of the band E, and also through the head of the leg F, as shown in Fig. 4.

In the journal A' of the hip-pieces is a circumferential groove, a², and the bolt e' is so 95 arranged that it enters this groove a² and so prevents the band E from slipping off the trunnion A', whether it be clamped or loose thereon. When the bolt e' is loosened, the band E may be freely turned on the journal or trunnion A', to permit the swinging of the side leg, F, in a plane parallel with the hip-pieces, and 100

the side leg, F, may also be swung relatively to the band E in a plane at right angles to the hip-pieces. When the bolt e' is tightened, the swinging of the side leg in either of these 5 planes is prevented by the clamping of the band E around the trunnion or journal A', and by the clamping of the trunnion e in the trunnion-bearing d' .

G, Fig. 3, represents a portion of the drill-10 back, which has a circular dovetailed projection, g , and the body portion B of the tripod is provided with a fixed jaw, h , and a movable jaw, h' , which are both dovetailed or beveled, and by which the circular dovetailed projection g may be clamped to the support or body B, so as to secure the drill in position. The movable jaw h' of the clamp is formed upon a lever, H, which is fulcrumed at h^2 , and by means of a bolt, I, may be held and adjusted 15 in the body portion or support B, so as to cause the movable jaw h' , in connection with the fixed jaw h , to clamp and hold the cylindric dovetailed projection g on the drill-back G.

As best shown in Figs. 1 and 2, the bolt I 20 has a T-shaped head, i , and the body B is cored out at b^2 , so that the bolt I, after its nut i' is removed, may be inserted through the body and through the hole h^3 , provided for it in the lever H, and then by applying and 25 tightening the nut i' , the lever H may be drawn up in a proper position in the body and the movable jaw held with clamping force therein, the T-shaped head i of the bolt I coming to a bearing against shoulders b^3 in the body B.

Referring now to Figs. 5, 6, and 7, J designates a collar or clamp split or divided at j , and having its divided ends connected by a bolt, k . By tightening or loosening the bolt 40 k the collar J may be clamped upon an upright column or an arm projecting therefrom, or may be loosened, so that it may turn upon or slide along said arm or column. The clamp or divided collar J is provided 45 with a fixed beveled or undercut clamping-jaw, h , and a correspondingly beveled or undercut movable clamping-jaw, h' , which latter is formed upon a lever, H, fulcrumed by a bolt, h^2 , and having in it a hole or opening, 50 h^3 , for the reception of a clamping-bolt, I. The collar or clamp J is cored out at the front, at b^2 , so that when the nut i' of the bolt I is removed the latter can be introduced from the front of the clamp J through the opening h^3 in the lever H, and the T-shaped head i will then come to a bearing against shoulders b^3 , provided in the body or clamp J. By tightening the nut i' on the bolt I the 55 movable clamping-jaw h' may be moved relatively to the fixed jaw h , so as to clamp or re-

lease the circular dovetailed projection g upon the drill-back G, a portion of which is shown in Fig. 5.

What I claim as my invention is—

1. In a support for a rock-drill, the combination, with a clamp or body to receive a dovetailed projection on the drill-back, and having upon its face a fixed jaw which is beveled or undercut, of a movable jaw also beveled or undercut and carried by a lever fulcrumed to the clamp or body, and a single bolt for adjusting the lever and movable jaw relatively to the fixed jaw, substantially as herein described.

2. In a support for a rock-drill, the combination, with a clamp or body having a fixed jaw upon its face, of a movable jaw carried by a lever fulcrumed to the clamp or body, and a bolt for adjusting the lever and movable jaw relatively to the clamp or body and fixed jaw, the clamp or body being cored out so that the bolt may be inserted through it from the face, and having shoulders against which the head of the bolt bears, substantially as herein described.

3. In a drill-tripod, the combination, with a body provided with a clamp in which the drill-back may be secured, and hip-pieces having projecting journals or trunnions, of divided bands fitted to said journals or trunnions, and front legs pivoted to the bands, whereby provision is afforded for the swinging of the front legs in planes parallel with and transverse to the hip-pieces, substantially as herein described.

4. In a drill-tripod, the combination, with a body provided with a clamp, wherein the drill-back may be secured, and hip-pieces having projecting journals or trunnions A', of the divided bands E, surrounding said journals or trunnions, the side legs, F, and the bolts e' , whereby the side legs are pivoted to said bands and the bands clamped upon the journals or trunnions, substantially as herein described.

5. In a drill-tripod, the combination, with a body provided with a clamp in which a drill-back may be secured, and hip-pieces provided with projecting journals or trunnions A', having circumferential grooves a^2 , of the divided bands E, surrounding said journals or trunnions, the side legs, F, and the bolts e' , which project into the grooves a^2 , and whereby the side legs are pivoted to said bands and the bands clamped upon the journals or trunnions, substantially as herein described.

H. C. SERGEANT.
